US0D1077765S

(12) **United States Design Patent** (10) **Patent No.:** **US D1,077,765 S**
(45) **Date of Patent:** **** Jun. 3, 2025**

(54) **TELEVISION RECEIVER**

(71) Applicant: **LG ELECTRONICS INC.**, Seoul (KR)

(72) Inventors: **Younghun Jang**, Seoul (KR); **Hyojin Won**, Seoul (KR); **Seokhyun Park**, Seoul (KR)

(73) Assignee: **LG ELECTRONICS INC.**, Seoul (KR)

(**) Term: **15 Years**

(21) Appl. No.: **35/521,636**

(22) Filed: **Jan. 9, 2024**

(80) **Hague Agreement Data**

Int. Filing Date: **Jan. 9, 2024**

Int. Reg. No.: **DM/235958**

Int. Reg. Date: **Jan. 9, 2024**

Int. Reg. Pub. Date: **Jul. 12, 2024**

(30) **Foreign Application Priority Data**

Jul. 18, 2023 (KR) 30-2023-0027700

(51) **LOC (15) Cl.** **14-03**

(52) **U.S. Cl.**

USPC **D14/126**

(57) **CLAIM**

The ornamental design for a television receiver as shown and described.

DESCRIPTION

1. Television receiver

1.1 : Perspective

1.2 : Back perspective view

1.3 : Front

1.4 : Back

1.5 : Left

1.6 : Top

1.7 : Bottom

The broken lines indicate portions of the article that form no part of the claimed design; the right side view is omitted because it is a mirror image of the left side view.

1 Claim, 7 Drawing Sheets
